Specification of Letters Patent.

Patented Feb. 6, 1917.

Application filed March 10, 1913. Serial No. 753,273.

To all whom it may concern:

Be it known that we, ALBERT J. MEIER and WILLIAM L. SWIFT, citizens of the United States, said ALBERT J. MEIER residing at Glendale, in the county of St. Louis, State of Missouri, and said WILLIAM L. SWIFT residing at the city of St. Louis, State of Missouri, have invented certain new and useful Improvements in Automatic Operating Means for Ticket Vending and Registering Machines, of which the following is a specification.

This invention relates to improvements in ticket vending and registering machines and more particularly to the machine of this character that is disclosed in United States Letters Patent No. 1,039,167, granted to Albert J. Meier and William L. Sullivan, September 14, 1912, for which Patent No. 1,039,212, for an improvement thereon was granted to William L. Sullivan, September 24, 1912, the object being to provide automatic operating means therefor.

In the accompanying drawings forming part of this specification, in which like numbers of reference denote like parts wherever they occur,

Figure 1 is a side elevation of a ticket vending and registering machine equipped with the automatic operating means which embodies the present invention;

Fig. 2 is a rear elevation of same;

Fig. 3 is a side elevation, on an enlarged scale, of the automatic operating means with the housing cover removed and some parts shown in section; and

Fig. 4 is a sectional view, on an enlarged scale, on the line 4—4, Fig. 1.

In the following description, some parts of the machine that are illustrated in the drawings are referred to by reference numerals to agree with the designations of the corresponding parts that are shown and described in the above-mentioned patents.

The top plate 1 of the machine extends beyond the side plate 4, and beneath this extension is located a plate 2, one side of which is supported by a laterally-projecting lip 3 or a plurality of such lips borne by the side plate 4 and is secured to said lip or lips by a screw 5 or a plurality of such screws or other suitable means, and the other side of

which is supported by a suspension rod 6 or a plurality of such rods, each rod being secured to a hanger 7 by a bolt 9 or other suitable means, which hanger is borne by the top plate 1. Nuts 10 on each suspension rod 6 hold the plate 2 firmly therebetween.

Supported upon the plate 2 and secured thereto by bolts 11 or other suitable means is a support or frame 13, which may be a casting as illustrated in the drawings, part of which forms the casing or frame of an electric motor. Another part of the support or frame 13 forms a housing 15, through a portion of the interior of which the shaft 16 of the motor 14 extends from the bearing 17, the end of said shaft being journaled in a thrust-box 18 having a thrust-screw 19, which thrust-box is secured in an opening 20 in the housing 15 by screws 21 or other suitable means. A worm 22, which is mounted on the shaft 16 intermediate the bearing 17 and the thrust-box 18 and is secured to said shaft by a set-screw 23 or the like, meshes with and drives a worm-gear 24 counter-clockwise, Fig. 3, which worm-gear is revolubly mounted on an antifriction collar or bushing 25, which is revolubly mounted on a counter-shaft 26. Said worm-gear 24 may be spaced from the bearing 17 by a washer 27 or a plurality of such washers mounted on the shaft 16. The counter-shaft 26 is journaled in an opening 28 in an extension 29 of the housing 15 and, also, in an opening 30 in a boss 31 borne by the cover 32 of the housing 15, which cover is secured in place by screws 33 or other suitable means. Oil-cups 16^a on the housing 15 affords means for lubricating the shaft 16 and the worm 22.

The worm-gear 24 has a circular recess 34 in one of its faces to receive a disk 35, which is mounted on the counter-shaft 26 and secured thereto by a pin 36 or other suitable means, there being sufficient space between the periphery of the disk 35 and the peripheral wall of the recess 34 to allow said worm-gear normally to rotate idly upon the counter-shaft 26. A clutch-plate 37 is revolubly mounted on the counter-shaft 26 and is preferably located adjacent to the disk 35 within the recess 34 in the worm-gear 24. Each end of the clutch-plate 37 is provided with an elongated notch 38 to receive the

2
 reduced end 39 of a roller 40, which is located in a notch 41 in the periphery of the disk 35, there being as many notches 41 as rollers 40. Each notch 41 is formed relatively deep at one end thereof and is provided with a cam surface 42, which slopes toward the peripheral wall of the recess 34 in the worm-gear 24 so as to form a tapered space 43 between same and the peripheral wall of said recess. By this arrangement, when the rollers 40 stand at the deep ends of the notches 41 as depicted in Fig. 3, the disk 35 and the counter-shaft 26 will remain stationary while the worm-gear 24 rotates, but, when the rollers 40 are moved into the tapered spaces 43 in the manner hereinafter described, so as to become wedged between the cam surfaces 42 of the notches 41 and the peripheral wall of the recess 34, said rollers will thereby frictionally connect the disk 35 with the worm-gear 24, with the result of causing said disk and the counter-shaft 26 to rotate therewith.

While, for the purpose of illustration, the disk 35 is shown with a pair of notches 41 formed in its periphery, which notches are preferably located diametrically opposite each other, yet, it should be understood that said disk may have only one notch 41, in which event only one roller 40 and a clutch-plate 37 having only one notch 38 would be used, or, if desired, the disk 35 may have three or more notches, under which circumstances, three or more rollers 40 and a clutch-plate having three or more notches 38 would be utilized.

A pin 44, which is secured to the clutch-plate 37, extends through an arcuated slot 45 in the disk 35 and projects from said slot 45 into a circular recess 46 within the housing 15. A bar or pin 47 is reciprocatively mounted in an opening 48 in the housing 15, so that its inner end projects into the path of rotation of the pin 44 within the recess 46 and normally occupies a position in front of and in engagement with one side of said pin 44, thereby holding the latter in the rear end of the slot 45 in the disk 35 as depicted in Fig. 3, so as to hold the clutch-plate 37 normally in position to hold the rollers 40 in the deep ends of the notches 41. A spring 49 attached to an arm 50 borne by the clutch-plate 37 and, also, to a pin or stud 51 borne by the disk 35 tends to rotate the clutch-plate 37 counter-clockwise, Fig. 3, and, when the bar 47 is moved from in front of the pin 44 as hereinafter described, the spring 49 rotates the clutch-plate 37 counter-clockwise on the counter-shaft 26 and thereby causes said clutch-plate to move the pin 44 toward the front end of the slot 45 and, also, to move the rollers 40 into the tapered spaces 43 until said rollers become wedged between the cam surfaces 42 and the peripheral wall of the

recess 34 in the worm-gear 24, whereupon the disk 35 and the counter-shaft 26 rotate with the worm-gear 24. In this way, the disk 35 is automatically connected with the worm-gear 24, whereby the counter-shaft 26 will continue to rotate with the latter as long as the bar 47 is held out of the path of rotation of the pin 44. In order to stop the rotation of the counter-shaft 26, the bar 47 is moved in the manner hereinafter described, so as to project into the path of rotation of the pin 44, so that, when said pin 44 strikes the bar 47, the former will be moved toward the rear end of the slot 45 and will rotate the clutch-plate 37 clockwise, Fig. 3, whereby said clutch-plate will move the rollers 40 toward the deep ends of the notches 41 so as to release said rollers from their wedged engagement with the cam surfaces 42 and the peripheral wall of the recess 34 in the worm-gear 24, with the result of automatically disconnecting the disk 35 from the worm-gear 24 so as to allow the latter to rotate idly while the disk 35 and the counter-shaft 26 remain stationary.

In order to operate the bar 47 in the manner hereinabove described, the outer end of same bears a laterally-projecting pin 52, which projects into an elongated notch 53 in the end of one arm of a bell-crank 54, the latter being pivotally attached at 55 to a bracket 56 borne by the extension 29 of the housing 15. The other arm of the bell-crank 54 is pivotally connected at 57 to the lower end of a link 58, the upper end of said link being pivotally connected at 59 to one end of a lever 60, which is pivoted at 61 to a lug 62 borne by the side plate 4. The other end of the lever 60 extends between the forks 63 of the bifurcated end of a button 64 and contains a slot 65 to receive a pin 66, which connects said forks, there being an opening in the top plate 1 through which the upper end of said button extends and projects above said top plate. A spring 67, which is attached to the lever 60 and, also, to a stud or pin 68 borne by the side plate 4, tends to rock the lever 60 counter-clockwise, Fig. 3, so as normally to hold the bar 47 in the path of rotation of the pin 44 and to cause the upper end of the button 64 to extend above the top plate 1 and, furthermore, to return same to such positions, said button being provided with an annular rib 69 or other suitable means adapted to engage the lower side of said top plate so as to limit the upward movement of said button. By this arrangement, when the button 64 is depressed, same will rock the lever 60 clockwise, Fig. 3, whereby the link 58 will cause the bell-crank 54 to rock counter-clockwise, Fig. 4, so that said bell-crank will withdraw the bar 47 from in front of the pin 44, so as to allow the disk 35 and the coun-

ter-shaft 26 to rotate with the worm-gear 24 as hereinabove described, but, as soon as the pressure is removed from the button 64, the spring 67 returns the button 64, lever 60, and the parts connected therewith to their initial positions and thereby moves the bar 47 into the path of rotation of the pin 44 so as to stop the rotation of the disk 35 and the counter-shaft 26 as hereinabove described.

The counter-shaft 26 projects from the end of the extension 29 of the housing 15 and supports an arm 70, which is secured thereto by a pin 71 or other suitable means.

15 A link 72 is pivotally attached to this arm 70 by means of a stud 73 having an anti-friction collar 74 revolvably mounted thereon. The lower end of the link 72 is pivotally attached to a plate 75 by means of a 20 stud-bolt 76, which extends through a slot 77 in the division plate 8 of the machine, said plate 75 having an end 78 thereof bent so as to extend through another slot 77 in said division plate, which bent end 78 bears 25 ears 79 to retain same within said slot. This plate 75 is located below the operating bar 93, and the slots 77 are preferably arranged substantially vertically so as to allow the plate 75 to reciprocate vertically, the operating bar being, also, mounted for vertical reciprocatory movement and being guided by the studs 107, which extend from the division plate 8 into slots 108, respectively, in said bar, as fully described in the above- 30 mentioned patents. The operating bar 93 is connected to the plate 75 by means of a spring 80 or a plurality of such springs. For the purpose of illustration, a pair of springs 80 is depicted in the drawings, each having links 81 attached to the ends thereof, there being an opening 82 in each of said links. The plate 75 bears a pair of laterally-projecting arms 83 to which the links 81 borne by the lower ends of the springs 80 are attached, respectively, and the operating bar 93 bears a pair of laterally-projecting arms 84 to which the links 81 borne by the upper ends of the springs 80 are attached, respectively, each arm 83 being provided with a notch 85 in its lower edge and each arm 84 being, likewise, provided with a notch 85 in its upper edge so that, when the links 81 are hooked over the ends of said arms by allowing said ends to extend through the openings 82 in said links, the pull of said springs holds said links in said notches. The pull of the springs 80 holds the plate 75 normally in its highest position so that the link 72 holds the arm 70 on the counter-shaft 26 nearly in an upright position so as to hold the disk 35 with the rear end of the slot 45 in engagement with the pin 44, in order to hold the latter in engagement with the bar 47. By this arrangement, when the bar 47 is withdrawn from

in front of the pin 44 so as to allow the clutch-plate 37 to connect the disk 35 with the worm-gear 24 as hereinabove described, the counter-shaft 26 then rotates with said worm-gear and thereby causes the link 72 70 first to lower and then to raise the plate 75 during each complete revolution of said counter-shaft. Each time the plate 75 is moved downwardly, same stretches the springs 80, which, in turn, pull the operating bar 93 downwardly, but, when the plate 75 is moved upwardly, the springs 80 relax and allow the operating bar 93 to return to its initial position.

As fully described in the above-mentioned Patent No. 1,039,167, the operating bar 93 is operatively connected with the chain 87 by means of which the ticket-severing mechanism, the ticket-feeding mechanism, the ticket-registering mechanism, and the parts 80 35 connected therewith (not shown in the drawings) are operated, said chain passing over and in engagement with the sprocket-wheel 94 borne by the shaft 95 and being attached to the spring 100 in the usual manner, which spring holds same in and returns same to its initial position. The rotation of the shaft 95 is controlled, as described in that patent, so that same will normally limit the movement of the chain 95 90 100 to such extent that the ticket-feeding mechanism will cause one ticket from the roll 12 to be issued from the machine. The buttons 121 control the usual mechanism 105 (not shown) by means of which the shaft 95 is permitted to rotate sufficiently to allow greater movement of the chain 87, so as to issue two, three, four, five, or more tickets from the machine by merely depressing the proper button 121.

It should be understood that, instead of using an electric motor as hereinabove described, any other kind of a motor may be used, or the shaft 26 may receive its power from any suitable source. Furthermore, various minor changes in the construction and arrangement of parts may be made without departing from the nature and spirit of the present invention.

The operation of the machine is as follows:

The motor 14 is set into operation in the usual manner so as to rotate the worm 22, which in turn, drives the worm-gear 24 in the direction of the arrow, Fig. 3. If it is desired 120 to issue one ticket from the machine, it is only necessary to depress the button 64 so as to rock the lever 60, which, through the medium of link 58, causes the bell-crank 54 to withdraw the bar 47 from in front of the pin 44, whereupon the spring 49 rocks the clutch-plate 37 counter-clockwise, Fig. 3, whereby said clutch-plate causes the rollers 40 to become wedged between the cam surfaces 42 and the peripheral wall of the 125 130

recess 34 in the worm-gear 24, with the result of causing the disk 35 and the counter-shaft 26 to rotate with said worm-gear. During the first half of the revolution of the counter-shaft 26, the arm 70 causes the link 72 to move the plate 75 downwardly, whereby the latter stretches the springs 80 and thereby causes the operating bar 93 to descend and actuate the chain 87, which, in turn, actuates the mechanism to issue a ticket from the machine and, also, the mechanism to register the issuance of the ticket in the usual manner. During the last half of the revolution of the counter-shaft 26, the arm 70 causes the link 72 to raise the plate 75, thereby relaxing the springs 80 and allowing the operating bar 93 and parts connected therewith to return to their initial positions. As soon as the ticket appears above the top plate of the machine or at any other time before the counter-shaft 26 makes a complete revolution, the pressure is released from the button 64 in order to allow the spring 67 to return same, the lever 60, link 68, bell-crank 54, and bar 47 to their normal positions, so that, when the pin 44 engages the bar 47, the clutch-plate will move the rollers 40 out of their wedged engagement with the cam surfaces 42 and the peripheral wall of the recess 34 in the worm-gear 24, with the result of stopping the rotation of the counter-shaft 26.

In case two or more tickets are to be issued from the machine, the proper button 121 is depressed, after which the button 64 is depressed so as to allow the counter-shaft 26 to rotate with the worm-gear 24 and to cause the link 72 to move the plate 75 downwardly, thereby stretching the springs 80, which cause the operating bar 93 to descend until the chain 87 has rotated the ticket-feeding drum in the usual manner sufficiently to issue the desired number of tickets from the machine, the button 64 being released before the counter-shaft 26 makes a complete revolution, so as to stop the latter upon the completion of one revolution.

It will be evident that, if it is desired to issue two or more tickets, successively, it is only necessary to depress the button 64 and to keep same depressed so as to hold the bar 47 out of the path of rotation of the pin 44, in order to allow the counter-shaft 26 to continue to rotate until the last ticket of the desired number appears above the top plate of the machine or until any other time intermediate the starting and completion of the last revolution of said counter-shaft necessary to issue the last ticket of the desired number, whereupon the pressure is removed from the button 64 in order to allow the spring 67 to restore the bar 47 to its initial position in the path of rotation of the pin 44 as hereinabove described, so as to stop the rotation of the counter-shaft 26

at the completion of the last revolution necessary to issue the last ticket of the desired number.

We claim:

1. In combination with a ticket vending and registering machine and an actuator therefor, a driven member, a shaft, clutch mechanism for operatively connecting said shaft with said member, a reciprocatory member operatively connected with said shaft, and means connecting said reciprocatory member with the actuator.

2. In combination with a ticket vending and registering machine and an actuator therefor, a driven member, a shaft, clutch mechanism for operatively connecting said shaft with said member, a reciprocatory member operatively connected with said shaft, and resilient means connecting said reciprocatory member with the actuator.

3. In combination with a ticket vending and registering machine and an actuator therefor, a driven member, a shaft, clutch mechanism for operatively connecting said shaft with said member, an arm borne by said shaft, a reciprocatory member operatively connected with said arm, and means connecting said reciprocatory member with the actuator.

4. In combination with a ticket vending and registering machine and an actuator therefor, a driven member, a shaft, clutch mechanism for operatively connecting said shaft with said member, an arm borne by said shaft, a reciprocatory member, a link connecting said reciprocatory member with said arm, and means connecting said reciprocatory member with the actuator.

5. In combination with a ticket vending and registering machine and an actuator therefor, a driven member, a shaft, clutch mechanism for operatively connecting said shaft with said member, an arm borne by said shaft, a reciprocatory member, a link connecting said arm with said reciprocatory member, and resilient means connecting said reciprocatory member with the actuator.

6. In combination with a ticket vending and registering machine and actuating means therefor, a shaft operatively connected with the actuating means, a driven member revolvably mounted on said shaft, automatic clutch mechanism for connecting said shaft with said member, a depressible button, and means operated by said button for controlling said clutch mechanism.

7. In combination with a ticket vending and registering machine and actuating means therefor, a shaft operatively connected with the actuating means, a driven member revolvably mounted on said shaft, automatic clutch mechanism for connecting said shaft with said member, means normally holding said clutch mechanism in inoperative position, a depressible button, and

means operatively connecting said button with said holding means.

8. In combination with a ticket vending and registering machine and actuating means therefor, a shaft operatively connected with the actuating means, a driven member revolubly mounted on said shaft, automatic clutch mechanism for connecting said shaft with said member, means normally holding said clutch mechanism in inoperative position, a deppressible button, means operatively connecting said button with said holding means, and means for restoring said holding means and said button to normal position upon the release of said button.

9. In combination with a ticket vending and registering machine and actuating means therefor, a motor, means operatively connecting said motor with the actuating means, clutch mechanism controlling said connecting means, a deppressible button, and means operatively connecting said button with said clutch mechanism.

10. In combination with a ticket vending and registering machine, motor driven rotating means, a normally stationary rotatable member, means connected to the member for actuating said machine to issue a ticket and to operate the register upon the first half of the revolution of the member and for allowing said machine actuating means to return to normal position during the last half of the revolution of the member and means to connect the rotating means and the member to effect movement of the latter from the rotating means.

11. In combination with a ticket vending and registering machine, and actuating means therefor, reciprocatory means in connection with the actuating means which re-

ciprocating means when moved in one direction operates said actuating means to cause the machine to issue a ticket and register same and which when moved in the opposite direction allows said actuating means to return to normal position, driven means, normally stationary means connected to the reciprocatory means to actuate the latter and manually operable means for connecting the driven and normally stationary means throughout any selected predetermined period.

12. In combination with a ticket vending and registering machine and an actuator therefor, driving means, normally stationary rotatable means, means connected to said rotatable means for operating the actuator and returning same to normal position upon each revolution of the rotatable means, and means to connect the driving means with the rotatable means to operate the latter from the driving means.

13. In a ticket vending and registering machine operated by a motor, a manually controlled ticket feeding and registering mechanism, whereby the operator may set the machine to issue one or more tickets, and a second manually operated means to control the revolutions of the shaft of the motor, and an operative connection between said shaft and the ticket feeding and registering mechanism.

In testimony whereof we hereunto affix our signatures in the presence of two witnesses.

ALBERT J. MEIER.
WILLIAM L. SWIFT.
